UNITED STATES PATENT OFFICE.

ARTHUR TREVOR DAWSON AND GEORGE THOMAS BUCKHAM, OF WESTMINSTER,
LONDON, ENGLAND, ASSIGNORS TO VICKERS LIMITED, OF WESTMINSTER,
LONDON, ENGLAND.

FIRING MECHANISM OF BREECH-LOADING GUNS.

1,299,139.

Specification of Letters Patent. Patented Apr. 1, 1919.

Application filed June 21, 1917. Serial No. 176,110.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Firing Mechanism of Breech-Loading Guns, of which the following is a specification.

This invention relates to firing mechanism in which there is interposed between the trigger or firing handle and the sear of the striker or firing needle, a spring controlled member which, when released by the trigger, serves to transmit to the striker sear the necessary movement for disengaging it from the striker.

According to the invention we provide in an automatic gun means whereby the aforesaid spring controlled member is automatically re-cocked during the recoil of the barrel in "single fire" operation, the said means preferably comprising a cam carried by the operating crank of the breech mechanism or by any other suitable part contiguous to and moving with the crank. The said spring controlled member may be in the form of a plunger with which engages a sear which is herein referred to as the secondary sear to distinguish it from the striker sear. This secondary sear is adapted to be displaced to release the spring controlled plunger by a spring controlled slip pawl or tripping piece which is suitably connected to the trigger or firing handle. Means may be provided by the adjustment of which the said slip pawl or tripping piece can at will be caused to perform its tripping function in relation to the secondary sear (thereby firing single shots) or can be prevented from performing this function in which event the firing mechanism is set for the automatic operation of the gun. The said means may also be adjusted to a "safe" position in which condition the secondary sear is prevented from being disengaged from the spring plunger and the gun cannot then be fired. It may happen that during the firing of the gun the lock does not quite reach its forward or firing position, the actuating handle on the crank shaft in consequence

being out of contact with its limit stop. When this occurs it is customary to strike 55 the actuating handle smartly to bring it against its limit stop and move the lock to its forward position; it has been found that in effecting this operation the gun is liable to be prematurely fired. In order to obviate 60 such premature firing we provide means for preventing the aforesaid spring controlled plunger from being liberated until the lock approaches its firing position. These means may comprise a safety sear for engaging with a member moving with the spring controlled plunger, this safety sear being disengaged from the said member as the crank shaft completes its movement to bring the lock to its firing position.

In order that the said invention may be clearly understood and readily carried into effect we will describe the same more fully with reference to the accompanying drawings, in which:—

Figure 1 is a side elevation showing more or less diagrammatically a constructional form of the invention embodied in an automatic gun of the Maxim type, one side of the breech mechanism casing of the gun having been removed to illustrate the invention more clearly.

Fig. 2 is a plan of Fig. 1 with parts thereof in section on the lines 1, 1 and 2, 2 of Fig. 1.

Fig. 3 is a side elevation, viewed in the direction of the arrow in Fig. 2, of the change fire device.

Fig. 4 is a side elevation of Fig. 3.

Fig. 5 and 6 are views similar to Figs. 1 and 2—but with the muzzle of the gun directed toward the left—illustrating a constructional form of the means for preventing the gun from being prematurely fired.

Fig. 7 is a section taken approximately on the line 3, 3 of Fig. 5 and viewed from the left.

Fig. 8 is a section taken approximately on the line 4, 4 of Fig. 5 and viewed from the right.

A is the mechanism casing of the automatic gun; A' is the operating crank of the breech mechanism and A² is the crank shaft. A³ represents the aforesaid cam moving with the crank A'. B is the striker sear. C

represents the spring controlled plunger and D represents the secondary sear appertaining to this plunger. E represents the spring controlled slip pawl or tripping piece for disengaging the said secondary sear from the plunger C. E² (Figs. 5 to 7) represents the aforesaid safety sear for preventing premature firing of the gun.

In the example shown the spring plunger 10 C is connected by a pin e to a longitudinally displaceable rod C' whose forward end is pivoted to an arm C^{2x} rigid with an arm C² lying in contact with the striker sear B. The rear end of this rod is connected to one arm 15 c' of a bell crank lever pivoted to the mechanism casing A, the other arm c² being adapted to be operated upon by the aforesaid cam A³ on the crank A' of the breech mechanism. The secondary sear D is of bell 20 crank formation; its horizontal arm has a nose-piece engaging with a recess or shoulder of the spring plunger C and its vertical arm is arranged contiguous to the aforesaid spring controlled tripping piece E; the latter is pivoted to the rear end of a sliding rod E' suitably connected to the trigger or firing handle which is not shown. When the trigger is arranged on the elevating or training handwheel or lever, the connecting means 25 30 comprise a bell crank lever e' and a sliding pin e disposed co-axially with respect to the trunnions e^x.

The plunger C, the secondary sear D and the tripping piece E are arranged within a 35 casing F upon the outside of which is pivoted a "change over" lever F' provided within the casing with a curved arm f pivoted at f^x to the casing F and provided with a stop f'. This stop is adapted to occupy 40 three different positions by moving the arm f about its pivot; in the first or "safety" position which is that shown in Fig. 1 the stop co-operates with the vertical arm of the secondary sear D to prevent it from being 45 coming disengaged from the plunger C; in the second or "automatic fire" position, which is indicated by the numeral 1 in Fig. 1, the stop f' is situated above the upper surface of a recess in the tripping piece E when 50 the latter is displaced toward the left to fire the gun and this tripping piece is thereby prevented from performing its "slip" function; in the third or "single fire" position which is indicated by the numeral 2 in Fig. 55 1, the stop f' is situated contiguous to an upward projection on the tripping piece so that when the latter is displaced to fire the gun it is moved by the stop into the position shown by chain lines in Fig. 1 and is 60 thereby "slipped" from the secondary sear D.

When the change over lever F' and the stop f' are in the "single fire" position, the plunger is re-cocked by the aforesaid cam A³ on the operating crank A'. When the said 65 lever and stop are in the "automatic fire" po-

sition, the secondary sear D is retained out of engagement with the plunger C as long as pressure is exerted upon the trigger or firing handle; in this condition of affairs the striker sear B is released automatically as 70 the barrel approaches or reaches its forward position after recoil, by the co-operation of part of the barrel extension with the striker sear.

The initial manual cocking of the plunger 75 C prior to automatic or single fire operation is effected by the usual hand lever (not shown) on the outer part of the crank shaft A².

When this hand lever is actuated the 80 aforesaid cam A³ on the crank A' depresses the bell crank lever c', c² which is connected to the longitudinally displaceable rod C', and compresses and re-cocks the spring plunger C.

The safety sear E² (see Figs. 5 to 7) is pivoted at e² to a fixed bracket E³ between which and the safety sear a spring e³ (Fig. 5) is interposed; this spring tends to hold the safety sear in engagement with an extension c'^x of the arm c' so that a shoulder on the safety sear E² (see Fig. 5) prevents the arm c' and therefore the spring plunger C from moving to liberate the striker sear B. The safety sear E² has an arm E^{2x} which lies 95 in the path of a projection A⁴ moving with the crank shaft A². In the example shown this projection is carried by the aforesaid cam A⁸ and is so arranged that as the crank shaft completes its movement to bring the 10 lock to its firing position, the projection will come against the arm E^{2x} and disengage the safety sear E² from the extension c'^x of the arm c'.

What we claim and desire to secure by 1 Letters Patent of the United States is:—

1. An automatic gun having firing mechanism comprising a spring controlled member which, when released, transmits movement to the striker sear for releasing the 1 striker, and provided with means whereby the said member is automatically re-cocked during recoil of the barrel in "single fire" operation.

2. In an automatic gun, the combination 1 with the operating crank of the breech mechanism and firing mechanism comprising a spring controlled member which, when released, transmits movement to the striker sear for releasing the striker, of means moving angularly with said crank for automatically re-cocking said member during recoil of the barrel in "single fire" operation.

3. In an automatic gun, the combination 1 with the operating crank of the breech mechanism and firing mechanism comprising a spring controlled member which, when released, transmits movement to the striker sear for releasing the striker, of a cam moving with the said operating crank in such

manner that when the said crank is displaced during hand operation and during recoil of the barrel in single fire operation it cocks the said spring controlled member.

5 4. In an automatic gun, the combination of a spring controlled member which when released transmits movement to the striker sear for releasing the striker, a sear engaging with the said member, a slip pawl or 10 tripping piece for displacing the latter sear to release the spring controlled member and means for at will causing the pawl or tripping piece to perform or preventing it from performing its tripping function, substantially as described.

15 5. An automatic gun provided with firing mechanism comprising a spring controlled member which when released transmits to the striker sear the necessary movement for 20 disengaging it from the striker, means for automatically re-cocking the said member during the recoil of the barrel in "single" fire operation and means for preventing the said member from disengaging the striker

sear until the lock approaches its firing po- 25 sition.

6. An automatic gun provided with firing mechanism comprising a spring controlled member which when released transmits to the striker sear the necessary movement for 30 disengaging it from the striker, means for automatically re-cocking the said member during the recoil of the barrel in "single" fire operation, a safety sear adapted to prevent firing movement of the said member and a projection moving with the crank shaft of the breech mechanism for displacing the safety sear to liberate the spring controlled member as the lock approaches its 35 firing position.

In testimony whereof we have hereunto affixed our signatures.

ARTHUR TREVOR DAWSON.
GEORGE THOMAS BUCKHAM.
